UNITED STATES PATENT OFFICE.

BENJAMIN F. WILLARD AND STATES R. CROWNER, OF SPRINGVILLE, IOWA.

DESIGN FOR A KITCHEN-CABINET.

SPECIFICATION forming part of Design No. 30,504, dated April 4, 1899.

Application filed February 17, 1899. Serial No. 705,897. Term of patent 14 years.

To all whom it may concern:

Be it known that we, BENJAMIN F. WILLARD and STATES R. CROWNER, citizens of the United States, and residents of Springville, in the county of Linn and State of Iowa, have invented and produced a new and original Design for Kitchen-Cabinets, of which the following is a specification, reference being had to the accompanying drawing, forming part thereof.

The figure is a perspective view of our cabinet, showing its exterior configuration.

The letter A designates the skeleton frame and form that has a fixed top B and an upward extension C, that is provided with a hinged or movable cover D.

F is the top of a fixed back, and in front of it and on the fixed top B is a series of small drawers g. Under the fixed top B and in the end of the frame A is a series of drawers h, graduated in size and in three tiers.

Immediately under the top B is a space adapted to be filled with a molding-board, and immediately under that space are two drawers J of uniform size, and immediately under those mating drawers is a large drawer K. 25

In the bottom of the end portion of the frame A, that extends above the fixed top B, there is a drawer L.

These different distinct features are shown 30 in their relative positions and constitute the complete design.

Having thus described our invention, what we claim as new, and desire to secure by Letters Patent therefor, is— 35

The design for a kitchen-cabinet, as herein shown and described.

BENJAMIN F. WILLARD.
STATES R. CROWNER.
